UNITED STATES PATENT OFFICE.

ADAM BOHN, OF MERCER, PENNSYLVANIA.

PRUNING IMPLEMENT..

SPECIFICATION forming part of Letters Patent No. 399,370, dated March 12, 1889.

Application filed September 10, 1888. Serial No. 285,043. (No model.)

To all whom it may concern:

Be it known that I, ADAM BOHN, a citizen of the United States, residing at Mercer, county of Mercer, and State of Pennsylvania, 5 have invented certain new and useful Improvements in Pruning Implements, of which the following is a specification.

My invention relates to that class of pruning implements in which a curved knife-edged cutting-jaw is pivoted to a curved jaw forming a seat for the branch, twig, or other object to be severed, and in which the jaws are provided with handles and pivoted together, so as to open and close like ordinary shears.

The object of my invention is to form the jaws and their handles in the simplest and most inexpensive way, and to provide improved means for limiting the movement of 20 the jaws and the handles, so that they shall not move so far in one direction as to squeeze the hands of the operator, nor so far in the opposite direction as to throw the jaws out of their proper relative working position.

To this end my invention consists in forming the principal parts of the implement in three parts, the cutting-jaw and its handle being formed of a single piece of metal, and the opposite jaw and its handle also of a single piece of metal adapted to lie flat on the cutting-jaw and to be pivoted directly thereto by a pivot-pin, and in providing each handle near the junction with its jaw with an adjustable gage lug or block projecting in line with the pivot-pin, and provided with means for firmly securing it in its adjusted position, so as to permit the jaws to move more or less to accommodate the wear on the cutting-jaw incident to sharpening.

In the accompanying drawings, Figure 1 is a side view of the implement; Fig. 2, a detail view of the gage-block; and Fig. 3 is a section on the line 3 3 of Fig. 1, showing the manner of attaching the block to the implement.

The cutting-jaw *a* is made of steel, in one piece with the handle *b*. One side of the jaw and handle is made straight and flat, adapted to rest against the straight flat side of the jaw *c* and its handle *d*. The jaw *a* and the handle *b* are pivoted to the jaw *c* and handle *d* at *e* by a pivot-pin, *f*.

The cutting-jaw *a* is provided with a convex curved cutting-edge, *g*, and inclines on its outer side from the edge *g* to its rear edge, *h*. The jaw *c* is curved to form a concave recess, *i*, which forms a seat for the twig, branch, or other object to be severed. The cutting-edge *g* moves past the recess *i*, close to the side of the jaw *c*.

On the handles *b* and *d*, near the pivot *f*, 60 are arranged blocks *j* *k*, which project from the handles in opposite directions in line with the pivot-pin, so that the block *j* on the handle *b* will bear against the side of the handle *d* when the jaws are closed. The block *k* is 65 similarly arranged on the handle *d*, to bear against the handle *b*. By this means the inward movement of the handles is limited, so that they will not come so close together as to squeeze the hands of the operator, and the 70 jaws are prevented from moving past each other too far.

The blocks *j* and *k* are preferably formed as shown in Fig. 2. The block itself is rectangular, and is provided on its under side 75 with a shank, *l*, which is arranged eccentrically—*i. e.*, the edge of the block is close to the shank on one side. On the next side it is a little farther away. On the third side it is still farther away, and on the fourth side the 80 distance between the shank and the edge of the block is greatest.

The shanks *l* are seated in holes *m* in the handles and are held in place by set-screws *n*, extending into the sides of the handles and 85 bearing against the shanks. As the cutting-edge of the jaw *a* is worn away, it becomes necessary to adjust the blocks, so that the cutting-edge *g* may move a sufficient distance past the curved seat *i*. This is done by 90 turning the blocks to change the sides lying adjacent to the opposite edges of the handles. The sides having different distances from the shanks, the proper ones may be selected to properly adjust the movement of the jaws 95 and their handles.

The block *j* on the handle *b* limits the outward movement of the jaws and handles, as when the jaws are fully open the block *j* bears against the back of the jaw *c*.

The cutting-jaw may be sharpened without separating it from the jaw *c*, as the inclined

portion is on that side of the jaw removed from the jaw *c*.

The implement is strong and durable and works effectively. The blocks are not liable to get out of place, as they are adjusted by turning, instead of by a longitudinal movement toward and from the handles, and the set-screws hold them against turning when in use.

Having thus described my invention, what I claim as new, and desire to secure by Letters Patent of the United States, is—

The combination, substantially as hereinbefore set forth, of the cutting-jaw, its han-

dle, the opposite jaw formed with a concave seat and a handle, the pivot-pin connecting the two jaws, the gage-blocks, their eccentric shanks seated in sockets in the handles and adjustable therein, and the set-screws engaging with the shanks for firmly securing the shanks in their sockets.

In testimony whereof I have hereunto subscribed my name.

ADAM BOHN.
